UNITED STATES PATENT OFFICE.

WILLIAM KLOCKE, OF WOODHAVEN, NEW YORK, ASSIGNOR TO PRESSED BEARING COMPANY, INC., OF BROOKLYN, NEW YORK, A CORPORATION OF NEW YORK.

LINED BEARING.

1,331,961.

Specification of Letters Patent. Patented Feb. 24, 1920.

Application filed August 27, 1918. Serial No. 251,659.

To all whom it may concern:

Be it known that I, WILLIAM KLOCKE, a citizen of the United States of America, residing in Woodhaven, in the borough and county of Queens and State of New York, have invented certain new and useful Improvements in Lined Bearings, of which the following is a specification.

This invention relates to lined bearings, and is in the nature of an improvement over the method and product of my application filed May 31, 1916, Serial No. 100,874.

The general purpose of my improvement is to enable forming a lined bearing by rolling the lining, or softer metal, onto the body or harder metal, as distinguished from flowing or casting processes, and in a manner which permits of establishing a firm positive anchor for the lining metal, by an interlocking connection between the sheets.

The difficulty of attaining such an object is that the overhanging portion of an interlocking connection, such as a dove-tailed joint, prevents the ready rolling together of two metal sheets, and I have discovered a successful method which results in a sufficient dove-tailed connection to afford a firm interlock, and yet permits the soft lining metal to be rolled onto the harder metal of the body.

In the disclosure of my earlier application the metal body was knurled to provide anchoring abutments, but these were of a generally pointed character with no undercut or overhanging portions. While this arrangement afforded a more or less tight connection, it was not a secure bond, owing to the absence of any interlocking joint, for which a dove-tailed or overhanging portion would be required.

According to my present invention, the metal body is provided with a multiplicity of projections, preferably small, although possibly otherwise constructed, and each having parallel sides. Thus, where the projection is circular, it would be a portion of a cylinder, and where it is fashioned after a rib, it would be of rectangular formation, the essential characteristic being that the side walls maintain an approximate parallel relationship, the spaces between the projections being of complementary form, and likewise having parallel sides. Thus there is presented no overhanging or undercut portion, and it is readily possible to roll a

soft lining metal, such as Babbitt metal, onto the body and have it entirely fill the spaces between the projections mentioned. According to the preferred method of operation, a thin coating of soldering material is interposed between the sheets of lining and body metal, and this serves to unite the two parts when subjected to heat and pressure according to the method described in my previous application, although the soldering step is not indispensable to carrying out the purposes of this invention, and may in some cases be omitted.

The strip of lining metal is rolled onto the strip of body metal preferably while heated, and while the steps referred to above will serve to unite these strips after a fashion, they will not be secured by an interlocking bond until subjected to a further operation which results in imparting the final curve, of preferably cylindrical form, to the bearing. This is accomplished by pressing the lined bearing to the required curvature, after the lining metal has been affixed to the body metal by rolling it. The final operation of pressing the bearing to cylindrical form results in bringing the outer ends of the projections closer together, the body metal being harder than the lining, and imparting a corresponding taper or dovetailed shape to the spaces between the projections, and likewise to the lining metal in these spaces. The sides of each projection will remain always parallel to each other, but the different projections will assume a generally radial relationship with reference to the imaginary center of the bearing. This causes the spaces between two adjacent projections to be narrowed toward the outermost ends of the projections, densifying the lining metal still further at such point, and thereby effecting a tight mechanical grip upon the lining metal.

To these and other ends the invention consists in certain improvements and combinations of parts as will be hereinafter more fully described and pointed out in the claims at the end of the specification.

In the drawings,—

Figure 1 is a sectional view, illustrating the relation of the body and lining metal after they have been rolled together in the initial operation.

Fig. 2 is a sectional view, showing the same parts after being subjected to pressure

to impart a semi-circular formation to the bearing.

Fig. 3 is a plan view of a modification of the body metal, in which the projections are in the form of longitudinal ribs.

Fig. 4 is a similar view of a further modified form where the ribs run diagonally.

Fig. 5 is a similar view of another modification, in which the projections are in the form of rectangular pins.

Fig. 6 is a similar view of still another modification in which the projections take the form of cylindrical pins.

Fig. 7 is a perspective view, partly in section, showing a completed cylindrical bearing.

Fig. 8 is a perspective view, partially in section, of a completed semi-cylindrical bearing.

In the present disclosure which is to be considered as an example, or possible embodiment, and not as a necessary or limiting arrangement, A designates the hard metal forming the body while B is the soft or lining metal. The body A carries a multiplicity of projections C which engage the soft metal during the initial rolling operation, and cause it to be forced into the spaces between the projections. The body metal A and lining metal B are preferably in the form of strips which are applied together and rolled into engagement with each other by the application of heat and pressure, according to the method described in my application above-referred to. It is preferable to apply to one of the adjacent surfaces a coating of soldering material which acts as a binder between the metal parts, and assists in their union. The solder is particularly desirable for obtaining a close union between the molecules of the adjacent surfaces at every point, although not essential to producing an interlocking bond between the two parts of the bearing.

The opposite sides of each projection C are parallel to each other, as indicated by D and E, and likewise the spaces between the projections are bounded by parallel surfaces. This arrangement makes it possible to easily roll the soft lining metal onto the body metal, and completely fill all of the space between the different projections. The lined bearing is then subjected to a pressing operation, which brings it to a curved form, preferably semi-circular, as shown in Fig. 2, and it will be seen that this bending operation causes a change of contour of the space between each two projections. The space referred to is narrowed at its outermost end, caused by the approach toward each other of adjacent projections. In other words, when the lined bearing is bent to semi-circular form, the outer ends of the projections are closer together than their inner or base portions, so that while the sides of

each projection retain their original parallel relationship with each other, the spaces between the projections assume a tapered or dove-tailed formation, densifying the bearing metal toward the outer end, and thus interlocking with it.

The projections may be in the form of ribs, either at right angles or diagonal with reference to the sides of the strip, as shown in Figs. 3 and 4 respectively. In another modification, they may be square, assuming the form of rectangular pins, or again they may be round in the nature of cylindrical pins. In any of these suggested modifications, it will be understood that the projecting portions are formed integral with the hard metal body, and that the opposite sides of each projection are parallel to each other. In other words, the sides of the projections extend at right angles to the adjacent surfaces of the body, of which they form an integral part. Such a lined bearing may be formed into complete cylindrical shape, as shown in Fig. 7, or it may be cut to semi-cylindrical shape as in Fig. 8. In the latter, the lining is shown as provided with end flanges F extending into corresponding rabbeted portions in the bearing seat, although this forms no essential part of the present improvement.

While I have described the opposite sides of the projections as having parallel relationship with each other, it is my intention that they shall be approximately parallel, or of such similar formation as to readily permit rolling the lining metal onto the projections and filling the spaces therebetween during the rolling operation, while also causing a dove-tailed or interlocking engagement between the body and the lining when the parts are bent to semi-circular form. This dove-tailed or overhanging portion need not necessarily be extreme, but is sufficient to provide a positive interlocking bond, which will prevent separation of the lining from the body, irrespective of whether there is a soldered union between them or not. It will be understood that other changes in the invention may be made without departing from the underlying features of the improvement and the scope of the following claims.

What I claim is:—

1. The process of making lined bearings, consisting in forming a series of projections on a metal blank, each of the projections having opposite sides arranged in approximate parallelism, applying a sheet of lining metal to said blank, subjecting the lined blank to pressure, and pressing the lined blank into curved shape.

2. The process of making lined bearings, consisting in forming on a metal blank a multiplicity of projections having a form which permits of rolling a lining metal into

engagement therewith when flat and interlocks with the lining metal when bent, applying a sheet of lining metal to the blank by pressure, and pressing the lined blank 5 into curved form.

3. The process of making lined bearings, consisting in forming a metal blank to have a series of projections therein with the opposite sides of each projection approximately parallel, applying a sheet of lining metal to the blank with soldering material upon one of the adjacent faces, applying pressure to the lined blank to force the lining metal between said projections, and 15 pressing the lined blank to curved shape thereby forming tapering spaces between the projections and anchoring the lining metal.

4. A curved lined bearing consisting of 20 a curved metal body and a curved lining metal interlocked to the body by a series of projections on the body, the opposite sides of each of said projections being parallel.

5. A curved lined bearing consisting of 25 a curved metal body and a curved lining metal interlocked with the body by a series of projections on the body, the opposite sides of said projections being approximately parallel, and the opposite walls of 30 the spaces between the recesses having converging relationship, resulting in an interlocking connection between the body and lining.

6. A curved lined bearing consisting of a curved metal body and a curved lining 35 metal interlocked by a plurality of projections on the body having engagement with the lining, each of said projections having its opposite sides arranged in approximate parallelism to each other. 40

7. A curved lined bearing consisting of a curved metal body and a curved lining metal coextensive with the adjacent surface of the body, and interlocked by a multiplicity of closely arranged projections on the body 45 having engagement with the lining, each of said projections having its opposite sides arranged in approximate parallelism to each other.

8. A curved lined bearing consisting of 50 a curved metal body, a curved lining metal interlocked with the body by a plurality of projections on the body having engagement with the lining, and a soldering material interposed between the body and the lining. 55

9. A curved lined bearing comprising a metal body having a multiplicity of projections with their opposite sides in approximate parallelism, the spaces between the projections having a dovetailed form, and a 60 sheet of lining metal interlocked by said dovetailed spaces.

In witness whereof I have hereunto signed my name.

WILLIAM KLOCKE.
